UNITED STATES PATENT OFFICE.

JESSE R. SMITH, OF BENTON, ILLINOIS.

TIE-PULLER.

977,975.

Specification of Letters Patent.

Patented Dec. 6, 1916.

Application filed April 12, 1910. Serial No. 554,909.

To all whom it may concern:

Be it known that I, Jesse R. SMITH, a citizen of the United States, residing at Benton, in the county of Franklin and State of Illinois, have invented new and useful Improvements in Tie-Pullers, of which the following is a specification.

This invention relates to railroad tie pullers, and the object of the invention is to 10 improve the device upon which I have received United States Letters Patent #924,391, dated June 8th, 1909.

With the above object in view, the invention resides in the novel construction and 15 combination of parts hereinafter fully described and claimed.

In the accompanying drawings, Figure 1 is a top plan view of a device constructed in accordance with the present invention and 20 showing the same in a position for removing a tie. Fig. 2 is a longitudinal sectional view upon the line 2—2 of Fig. 1. Fig. 3 is a transverse sectional view upon the line 3—3 of Fig. 1. Fig. 4 is a perspective view 25 of the winch. Fig. 5 is a side elevation of the main ratchet wheel. Fig. 6 is a detail perspective view of the lower portion or socket piece of the operating handle.

In the device illustrated and described in 30 connection with my patented rail puller #924,391, above noted, the main ratchet wheel operating winch is connected with the said winch through the medium of a key. The ratchet wheel is provided with a 35 circular recess corresponding with the cross sectional contour of the winch and this means of attaching the ratchet wheel to the winch has been found by experience to be defective inasmuch as a key is frequently 40 broken when the winch is operated, thus necessitating great delay and annoyance. Furthermore the ratchet being keyed to the 45 winch is free to slide so that the socket piece of the operating handle as well as the ratchet wheel have been frequently worked away 50 from the key. These are the primary objections which the present application is designed to overcome, but there are other minor objections which will be apparent as the description progresses.

In the accompanying drawings the numerals 1 designate the blocks, which are similar in construction to my patented device, the same being provided with pivoted 55 hook blocks 2. The blocks 1, in the present instance, are connected together through the

medium of spaced rods 3, the same being connected in any suitable manner with the said blocks 1.

The numeral 4 designates the improved 60 winch. This winch is of the ordinary rounded cross sectional formation, but is provided with a pair of spaced collars or flanges 5. One end of the winch 4 adjacent the flange 5 is provided with a suitable 65 rounded bearing 6 which engages one of the rods 1. The member 6 is extended a suitable distance so as to be connected with the toothed wheel 7, and this toothed wheel is normally contacted through the medium 70 of a dog 9 which is pivotally connected with the member 1 as at 10. The toothed wheel 7 is retained upon the member 6 through the medium of a suitable flange or collar 11 which is connected with the said extension 75 through the medium of a bolt or other securing element. The opposite end of the winch 4, adjacent the flange 5 is provided with an enlarged rounded portion designated by the numeral 12. From this rounded 80 portion 12 extends a non-circular portion 13, and the non-circular portion is provided with a reduced rounded portion 14. The extension is further provided with a still smaller rounded portion 15 and this portion 85 of the winch terminates in a non-circular end designated by the numeral 16. The circular portion 15 is adapted for the reception of a toothed wheel 17 while the rounded portion 15 serves as a bearing for the block 90 1. The toothed wheel 17 is retained upon the end of the winch through the medium of a suitable collar or flange 18, similar to the flange or collar upon the opposite end of the 95 said winch and the block 1 is provided with a gravity dog 19 which engages the teeth of the wheel 17.

The numeral 20 designates the operating lever. This lever 20 has its lower portion provided with a socket piece 21, the latter 100 comprising a pair of downwardly extending arms 22 and 23. The arm 23 is provided with an enlarged circular opening 24, which is adapted when in position upon the winch 4 to engage with the rounded enlarged portion 12 thereof. The arms 22 and 23 are spaced apart a distance equaling the length of the non-circular portion 13 of the winch and the arm 22 is provided with a smaller circular opening 25 which is adapted 110 to engage with the similar circular portion 14 of the said winch. The socket piece

of the operating handle 20 is provided with a weighted pivoted dog 26, the purpose of which will presently be apparent.

The numeral 27 designates the winch operating ratchet wheel. This wheel 27 is provided with a central squared opening 28, the latter being adapted to engage the squared bearing surface 13 of the winch 4. It will be further noted that the arm 22 being provided with a small opening 25 engages the rounded portion 14 and contacts with the squared portion 13 of the winch so as to prevent the lateral movement of the handle in the direction of the flange 5. The brace block 1 engaging the still smaller rounded portion 15 of the winch and contacting with the shoulder provided between this portion and the portion 14 is effectively sustained against lateral movement and the brace rods 3 of this member connected with the opposite member 1 retain all of the members in their proper positions. Furthermore, the toothed wheel 7 being provided with a central squared opening and engaging the squared extremities of the winch bears against the toothed wheels 7 and 17 and through the medium of their securing collars 11 and 18 prevent the lateral movement of either of the said toothed wheels.

Each or either of the blocks 1 is provided with a suitable handle 29, whereby the device may be easily grasped and transported from place to place as desired, and in order to easily manipulate the dogs 9 and 19 these

members are provided with offset fingers 30 35 as clearly shown in the figures of the drawing.

Having thus fully described the invention, what I claim as new is:—

In a tie puller and replacer of the class 40 1 described, a flanged winch, blocks having handles supporting the winch, spacing rods for the blocks, toothed wheels upon the winch, pawls for the toothed wheels pivoted to the supporting blocks, one of the ends 45 of the winch being provided with a small rounded portion adjacent the toothed wheel, and an enlarged rounded portion adjacent one of the flanges of the winch, a squared portion between these rounded portions, a 50 ratchet wheel having a squared opening for the squared portion of the winch, a lever having a socket portion provided with a pair of spaced arms, one of said arms being provided with an enlarged circular opening, the second arm being provided with a reduced circular opening, these openings being adapted to straddle the ratchet wheel and to engage the large and the small circular portions of the winch, and a gravity 55 pawl pivoted to the winch and engaging the teeth of the ratchet wheel.

In testimony whereof I affix my signature in presence of two witnesses.

JESSE R. SMITH.
